UNITED STATES PATENT OFFICE.

OSCAR WIEDERHOLD, OF SUMMIT, NEW JERSEY.

DESIGN FOR AN ARMATURE.

SPECIFICATION forming part of Design No. 27,870, dated November 16, 1897.

Application filed October 2, 1897. Serial No. 653,860. Term of patent 14 years.

To all whom it may concern:

Be it known that I, OSCAR WIEDERHOLD, a citizen of the United States, residing at Summit, Union county, State of New Jersey, have 5 invented and produced a new and original Design for Armatures, of which the following is a full, clear, and exact description.

The leading feature of my design is an armature substantially as shown in the accompanying drawings, which exhibit an armature embodying my design, showing the same in perspective in Figure 1 and in face view in Fig. 2.

In the figures a curvilinear part *b* projects

from the body *a* and has a hook-shaped portion *c* extending therefrom. The curvilinear portion *b* is bounded by wall *d*, which extends upward at an angle from the part *b* of the armature and conforms generally in shape to the shape of the edge of the curvilinear portion. 15 20

What I claim is—

The design for an armature substantially as shown.

OSCAR WIEDERHOLD.
